UNITED STATES PATENT OFFICE.

TIMOTHY J. KELLY, OF PASSAIC, NEW JERSEY, ASSIGNOR TO BRIGHTON MILLS, A CORPORATION OF NEW JERSEY.

MECHANISM AND METHOD OF OPERATING ON CORDS OR THREADS.

Application filed May 16, 1923. Serial No. 639,277.

To all whom it may concern:

Be it known that I, TIMOTHY J. KELLY, a citizen of the United States, residing at Passaic, in the county of Passaic and State of New Jersey, have made certain new and useful Improvements in Mechanism and Methods of Operating on Cords or Threads, of which the following is a specification.

The invention relates to a novel method and mechanism for uniting threads and yarns, and more especially to such a method and mechanism for uniting the strands of two threads or yarns in pairs to form a smooth and substantially invisible juncture, preparatory to weaving or other textile and cordage operations.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Fig. 1 is a top plan, with parts broken away, of a mechanism embodying the invention;

Fig. 2 is a side elevation, with some parts broken away and in section, of the mechanism shown in Fig. 1; and

Fig. 3 is a fragmentary top plan, of a modified form of the central part of the mechanism shown in Figs. 1 and 2;

Fig. 4 is a fragmentary top plan showing the automatic spool guard;

Figs. 5 and 6 are similar fragmentary elevations, looking at Fig. 4 from the left, but showing the spool guard in different positions;

Fig. 7 is a fragmentary detail, partly in section, showing one form of spool guard; and

Fig. 8 is an elevation, looking at Fig. 7 from the left.

This application is a continuation in part of my copending application, Serial Number 488,178, filed July 28, 1921, the spool guard shown in Figs. 4 to 8 not being disclosed therein.

The present invention is directed to improved mechanisms and methods for efficiently and rapidly uniting the ends of cords or threads to be used in weaving fabrics, especially fabrics wherein special features are required, such as heavy and knotless cords or threads (cord fabric for automobile tires being an example), and for expeditiously and efficiently performing the cord or thread uniting operation and other operations for the purpose of increasing the output of the loom or other producing machines.

In accordance with one feature thereof, the invention has in view the uniting of the ends of two cords or threads without knots or protuberances or irregularities and at the same time preserving the strength, size, twist and appearance of the cords or threads at the place of juncture, so as to avoid impairment of the fabric.

The invention in the various aspects thereof, has wide application in the textile art, but it will be described exemplarily herein, as being applied to the winding of the thread of small spools upon large spools and the related operations, and also to the uniting of the thread of large spools to the thread of spools on the creels and leading directly into the loom.

Other features of the invention will be first disclosed in connection with the detailed description of the present preferred embodiment; and it will be understood that the preceding statement, as well as those following, are explanatory and exemplary of the invention and not restrictive thereof.

Referring now to the details of the em-

bodiment of the invention illustrated by way of example in the accompanying drawings, the machine is provided with a light but strong frame 1, composed preferably of angle iron of generally oblong form, having parallel sides and rounded ends, and preferably made endless through welding or uniting in other suitable manner. The frame is therefore light but strong and rigid, and is 5 adaptable for use with and without legs or a similar support, so that it may either be supported on another machine, or may be supported on the floor at a suitable height thereabove and so as to be freely movable 10 therealong. The various parts of the machine are preferably detachably supported upon this frame 1 by suitable means such as clamping screws and other screws.

Referring now in detail to the devices or 20 mechanism for clamping and tensioning the thread preparatory to untwisting, and to certain devices which participate in the foregoing operations and also in the thread untwisting, a support is provided carried on 25 the frame 1 and positionable or adjustable therealong. This support comprises a transverse bar 2, resting upon the horizontally-disposed part of the frame 1, and also a similar transverse bar 3, engaging on the 30 under side of the frame 1. Clamping screws 4 serve to clamp the bars 2 and 3 against the opposite sides of the horizontal part of frame 1 to hold the bars firmly in any desired position.

35 Mounted on the bar 2 is a cylindrical rod 5, extending transversely and nearly across the frame 1. A cord or thread clamping device is mounted upon the rod 5 so as to be angularly or rotatably movable thereon 40 under spring tension to place the threads to be united under tension and to compensate for the varying lengths of the threads through untwisting and retwisting. As embodied, a U-shaped frame 10 has side reaches 45 11, 12 and a bottom reach 13. The side reaches 11 and 12 are apertured near their bottom parts to receive the rod 5, whereby they are swingably mounted thereon. A spring 14 is coiled about the rod 5 with one 50 end fixed thereto and the other end passing through the reach 13 of the frame 10. This mounting is for the purpose of placing the thread clamps under tension.

55 Mounted upon the frame 10 are two clamping devices for clamping, respectively, the two threads which are to be united. As embodied, there is mounted in the upper end of the frame 10 a rod 18. Upon rod 18, at one end thereof, is a circular beveled 60 clamping member 19, and a like member 20, which are resiliently pressed together, and between which one of the threads is slipped and thereby is clamped. At the opposite end of the rod 18, with- 65 in the frame 10, are two thread-clamp-

ing members 21 and 22, which may be of like structure and operation with those already described. A spring 23 is coiled about the rod 18, and resiliently presses against the clamping members 20 and 22, 70 which are loose on the rod 18, to provide the resilient clamping action.

By the invention, a certain delimited length is established in the two threads, 75 within which length the twist is taken out of the strands to separate them, the corresponding strands of the two threads, considered in pairs, are then tied together at different points along the delimited length, and the substantially exact amount of twist 80 is reimpended to the delimited length, thereby restoring it to normal or standard appearance and strength. The clamps just described establish one end of this delimited length, and the bars 2 and 3 being movable 85 or positionable along the frame 1, provide for varying such delimited length as desired.

At the opposite end of the delimited 90 length of the threads or cords there are provided means for holding the threads and for untwisting them to separate the strands thereof, so that they may be tied together; for storing or recording the amount of twist removed; and for restoring the proper 95 amount of twist after the various pairs of strands of the two threads have been united. As embodied, a housing structure is mounted on the frame 1, at the right hand end thereof in Fig. 1, comprising a floor 30 and vertical ends 31 and 32. A cover 33, formed as a top and two sides, is adapted to slide over the two ends 31 and 32 to constitute a completely closed housing.

In accordance with certain features of 105 the invention, a full spool is carried by the untwisting and retwisting mechanism, and constitutes one of the termini of the delimited thread length. A motor 37 is mounted upon the floor 30 within the casing, and the 110 motor shaft 36 projects out through the front wall 31 of the casing.

In the form shown in Figs. 1 and 2, the 115 motor shaft 36 is provided at its outer end with a disc 38, from which projects a spindle 39, upon which the spool 40 of thread or yarn fits friction tight, the spindle 39 being preferably made tapering for this purpose.

A clip 41 is provided upon, or attached 120 to, one end of the spool 40, to hold the thread so as to cause it to untwist, and later to retwist, when motor 37 is running and the spool 40 is thereby rotated. With this form a reversing switch, either hand or automatic will be used, and may be of any convenient or known form, or like that shown in application Ser. No. 460,725 of Pearson and Kelly.

In Fig. 3, on the shaft 36 of motor 37 is 125

a spool support, such as a yoke 42, which supports a spindle 43, on which spindle a full spool 40 is mounted. A detent or clip 41^a mounted on the spool support may be employed to prevent undesired rotation of the spool 40 about its own axis. The detents or clips 41 and 41^a, it will be noted, serve as one of the means or devices for delimiting the length of thread to be untwisted, spliced and retwisted.

The clamping, untwisting and retwisting mechanism which cooperates with the thread held by the clamp 19—20 comprises a shaft 46, journaled in the housing end plate 31, and which extends alongside and parallel to the shaft 36. Fixed on shaft 46 is a clamping disk 47 and loose on shaft 46 is a cooperating beveled clamping disk 48, which is resiliently pressed against disk 47 by suitable means, such as a spring 49 coiled about shaft 46 and in compression between disk 48 and the hub of pulley 51. Pulley 51 is grooved and is fixed on shaft 46, outside the end plate 31 of the housing, and a like grooved pulley 52 is fixed on shaft 36, just behind flange 38. A belt 53 runs over the two pulleys, whereby spindle 39 and clamp 47—48 are rotated in unison.

As embodied, means are provided by the invention for automatically determining or controlling the untwisting and retwisting action of the mechanism, so as to stop the untwisting when the strands of the delimited portion are separated from each other. As embodied, the shaft 46 extends backwardly and has a bearing also in the rear end plate 32 of the housing. Shaft 46 is screw-threaded, as shown at 56, for a large portion of its length within the housing, and threaded on this portion of the shaft is a traveling nut 57. Nut 57 depends downwardly and in its bottom portion is apertured, and through this aperture there passes a stationary rod 58, which rod is supported at its ends in the end plates 31 and 32 of the housing.

Thus it will be seen that when the motor 37 is running, the spool 40, clamp 47—48 and shaft 46 will all rotate together, and nut 57 will travel along the threaded portion 56 of the shaft.

The means for preventing the mechanism just described jamming at the end of its travel which is shown and described in the parent application Ser. No. 488,178, may be employed, but need not be described in detail.

As further embodied, a switch-actuating rod 62 extends along beneath and parallel the rod 58, and is slidingly supported thereon by having one of its ends upturned and looped over rod 58, as shown at 63. Mounted on rod 62 so as to be slidable therealong is a collar 64, and a hook 65 is fixed to and projects upwardly from the collar. This hook takes over and is slidable along the

rod 58. Hooks 63 and 65 suspend rod 62 from rod 58 and permit it to slide therealong under the impulsion of traveling nut 57. The collar 64 is positionable or adjustable along rod 62 by suitable means such as a clamping screw 66 threaded into the collar to press upon the rod. A guide and support 61 is provided for rod 62.

At its forward end, switch-actuating rod 62 abuts against a switch operating lever 71, which lever is adjustably pivoted or hinged at 72 upon the housing plate 31. Mounted upon the base plate 30 of the housing is a switch 73, which is operated by a cord or other suitable connection 74 extending from the switch and fixed to lever 71. An aperture 75 is formed in the lever 71 for a safety device as will be hereinafter more fully described.

The pivot point 72 of lever 71 is made adjustable along the housing, as shown by bolt and slot connection 70, in Figs. 1 and 2, for the purpose of varying the pull on cord 74 for any given position of the nut 57 and stop 64, so as to allow for operating switch 73 at the proper time and also to allow sufficient play for the restoration of the switch mechanism to operative position, when the switch 73 is of the on and off type.

The switch 73 is also positionable or adjustable along the base for the same reason as switch lever 71 and cooperatively therewith, the adjustment of these two securing the necessary operating and restoring action of the switch for any relative positions of nut 57 and collar 64. That is, the switch lever 71 and the switch 73 are both positionable to assure the correct working of the switch for any set position of the stop mechanism. In the embodied form of positioning means for the switch 73, slots 79 and 80 are formed in the base plate 30, and screws 81 and 82 project through the base of the switch and through the two slots respectively, and are threaded into a clamping bar 83 beneath the base plate 30 of the housing. Thus the switch may be positioned at any point along the length of the two slots.

The manner of operation of the mechanism so far as described is substantially as follows:

The end of one of the threads to be united, is slipped into the clamp 47—48 and this thread at the other end of the delimited length is slipped into the clamp 19—20. The end of the other thread is slipped into clamp 21—22 and at the other end of the delimited length this thread is slipped into the clip 40 or 41^a. The frame 10 may be slightly tilted forward against the spring 4 to keep the threads under tension. This pivotal and spring mounting of the clamps also permits movement to and fro to compensate for the difference in the length of the thread due to the untwisting and to the retwisting.

When the threads are thus clamped, the nut 57 is at the right hand end of its travel, and the collar 64 is at the point to which the nut 57 will have advanced when the two threads are completely untwisted. To start the untwisting operation, switch 73 is thrown on by hand, which can be done by moving the lever 71, and this starts the motor 37. This rotates spool 40 and clamp 10 47-48 to untwist the delimited portions of the two threads, and the rotation of spool 40 keeps it in the same relative position with respect to its threads and prevents the creation of any back-twist.

15 As the untwisting proceeds, nut 57 travels along screw 56 and rod 58 to the left, and finally strikes the hook 65. As collar 64 is clamped on rod 62, this moves rod 52 longitudinally to the left, and by reason of the 20 end of the rod abutting on switch lever 71, that lever is rocked about its hinge 72, and thereby pulls on cord 74 and snaps the switch 73 and stops the motor.

This leaves the strands in the delimited 25 length of both threads entirely untwisted.

If for any reason nut 57 is permitted to run too far to the left, the rod 62 will not jam against the lever 71 for the reason that after the switch is thrown off, due to the 30 angular movement of the lever 71, rod 62 comes into alignment with the aperture 75 and will pass therethrough, thus preventing jamming of these parts. To prevent jamming of the nut 57 at the left hand end, it 35 will run out on the reduced and unthreaded portion 61.

Means are provided, largely as a matter of convenience, for locating the point of forming the knot in the various pairs of strands 40 and as embodied, the mechanism is equipped to tie three knots in three cord or three stranded threads. For this purpose, three pairs of supporting bars 85 and 86 extend across the frame 1, one resting upon and the 45 other passing beneath the horizontal part of the frame 1, and being clamped thereagainst by screws 87. Pins 88 project upwardly from the respective plates 85 past the untwisted strands to serve as markers 50 for the uniting point in the strands. If desired, the pins 88 may be adjustable along the plate 85 by means of series of holes 89 formed therein.

The operative takes one strand of one of 55 the threads and one strand of the other thread, and cuts them by the localizing aid of the corresponding pin 88, and ties them together. The mechanism is then reversed to return the normal twist to the thread in 60 any suitable manner, as by reversing the motor, and this may be done either by a hand-operated switch, or by an automatically operated switch of any known or suitable kind. For example, such a switch 65 mechanism as shown in Fig. 10 of the co-

pending application of Pearson and Kelly, Ser. No. 460,725, filed April 12, 1921, may be employed, which serves to stop the mechanism when the normal twist has been restored to the spliced or united thread. 70

In Figs. 4 to 8 are shown an embodiment of two forms of spool guard, applied to the hereinbefore described mechanism, one form being capacitated to prevent the spool being removed from its supporting and rotating spindle, once the untwisting operation has begun until the retwisting operation is completed. 75

In the automatic form of spool guard, as embodied, an arm 90, which is preferably 80 bent or elbowed, as shown in Figs. 5 and 6, is formed in the end portion of a rod 91. Rod 91 is rotatively journaled at 92, 93 and 94 on the machine frame, so that when the rod is rocked, the arm 90 will pass into and 85 out of position in front of the spool 40 when the spool is upon, and is rotated by, the spindle 39 to effect the untwisting and the retwisting, as shown in Figs. 5 and 6.

In the embodied form of operating means 90 for the spool guard lever 90, the rod 91 is provided medianly thereof with a relatively long offset portion 95, in the general form of a swingable bail, which extends substantially the whole length of the travel of 95 the nut 57^a. This nut is the same as, or corresponds to, the nut 57 already described, and shown in Figs. 1 and 2 of the drawings. In the present instance, the nut 57^a is provided with a wing 96, having an operating 100 surface 97, which is inclined outwardly and backwardly and is adapted to pass into and out of engagement with the bail portion 95 of the rod 91 thereby to swing lever 90 into and out of locking position with respect to 105 spool 40. A spring 98 impels the rod 91 and the guard lever 90 into the position of Fig. 5, that is, the open or spool-passing position.

In the operation of the mechanism just described, it may be regarded as in the position of Figs. 4 and 5, that is, the guard lever 90 is in the open or spool-passing position, and the spool 40 has been pushed onto, and is held angularly relatively to, the spindle 39, preferably by frictional engagement therewith. When the motor is started, the wing 96 of the traveling nut 57^a immediately strikes the bail 95, rocking it to the right from the position of Fig. 5 to that of Fig. 6, and the spool is thereby firmly locked in position upon the spindle 39. 110

During the untwisting operation, the nut 57^a travels to the left along the screw-shaft 56, and the wing 96 of the nut, sliding along the bail 95 is continuously in sliding engagement with the bail and holds thus the lever 90 in spool-locking position. This relation maintains throughout and at the end of the untwisting operation. During the retwist- 125 130

ing operation, the nut 57^a travels backwardly along the screw shaft 56, and at the end of the retwisting operation, the wing 96 passes just clear of the bail 95. Spring 98 immediately rocks rod 91 and guard lever 90 from the locking position of Fig. 6 to the open position of Fig. 5 and the spool may then be removed.

In Figs. 7 and 8, a locking latch is shown mounted in the end of the spindle 39, which is both hand-operated and spring-operated. As embodied, the end of the spindle is slotted, and a little bearing block 100 is fixed in the lower half of the slot by suitable means, such as pins 101 and 102. A bent latch lever 103 is pivotally mounted in the upper part of the slot by suitable means, such as a pivot pin 104. The inner end 105 of the latch 103 is upwardly and inwardly inclined, and is impelled into spool locking position by suitable means, such as a flat spring 106. The inner face of the outer end of the latch lever 103 constitutes with the corresponding face of the outer end of the block 100 a clamp for the thread; receiving the thread, holding it during the untwisting and retwisting operation, and thereafter releasing it.

When the spool is inserted, moving from left to right in Fig. 7, the inner or right-hand end of the spool will strike the upper inclined surface 105 of the latch lever, and will slide over the latch lever, and immediately after the spool has passed, the lever will snap back under the impulsion of spring 106 to the spool-locking position shown in Fig. 7. By depressing the part 105 slightly, the thread may be passed into the bite of the members 100 and 103 and thereby be clamped for the untwisting and retwisting operation. When the spool is to be removed, the part 105 may be pressed downwardly by the finger and the thread be thereby released from the clamp, and the spool slid off thereover. It will be understood that both spool guards may be used together or separately from each other. If desired, the thread clip or holder 180 may be employed, or any other known or suitable form, so far as concerns many features of the invention.

The invention in its broader aspects is not limited to the specific mechanisms shown and described but departures may be made therefrom within the scope of the accompanying claims without departing from the principles of the invention and without sacrificing its chief advantages.

What I claim is:—

1. A mechanism for splicing threads including in combination means for untwisting the strands of two threads one of which is wound on a spool and means for correspondingly rotating the spool to prevent the creation of back twist in its thread.

2. A mechanism for splicing threads in-

cluding in combination means for untwisting the strands of two threads one of which is wound on a spool and for retwisting the delimited length after splicing and means for correspondingly rotating the spool to prevent the creation of back twist during the untwisting and for restoring the normal twist.

3. A mechanism for splicing threads including in combination means for untwisting the strands of two threads one of which is wound on a spool, means for correspondingly rotating the spool to prevent the creation of back twist in its thread, and a device for preventing the thread unwinding from the spool.

4. A mechanism for splicing threads including in combination means for untwisting the strands of two threads one of which is wound on a spool and for retwisting the delimited length after splicing and means for correspondingly rotating the spool to prevent the creation of back twist during the retwisting and for restoring the normal twist in said length and a device for preventing the thread unwinding from the spool.

5. A mechanism for splicing threads including in combination a pair of clamps for delimiting a length of thread, one clamp being rotatable to untwist the delimited length of thread, a clamp and a spool holder for delimiting a length of another thread, the spool holder and the spool thereon being rotatable together, and means for rotating the rotatable clamp and spool holder to untwist the delimited length of thread.

6. A mechanism for splicing threads including in combination a pair of clamps for delimiting a length of thread, one clamp being rotatable to untwist the delimited length of thread; a clamp and a spool holder for delimiting a length of another thread, the spool holder and the spool thereon being rotatable together, and means for rotating the rotatable clamp and spool holder to untwist the delimited length of thread and for rotating the spool holder in the opposite direction to restore the normal twist after splicing the strands of the two threads.

7. A mechanism for splicing threads including in combination a pair of clamps for delimiting a length of thread, one clamp being rotatable to untwist the delimited length of thread, a clamp and a spool holder for delimiting a length of another thread, the spool holder and the spool thereon being rotatable together, means for rotating the rotatable clamp and spool holder to untwist the delimited length of thread, and means for gripping the thread at the spool.

8. A mechanism for splicing threads including in combination a pair of clamps for delimiting a length of thread, one clamp being rotatable to untwist the delimited

length of thread, a clamp and a spool holder for delimiting a length of another thread, the spool holder and the spool thereon being rotatable together, means for rotating the rotatable clamp and spool holder to untwist the delimited length of thread and for rotating the spool holder in the opposite direction to restore the normal twist after splicing the strands of the two threads, and means for gripping the thread at the spool.

9. A mechanism for splicing threads including in combination a pair of clamps for delimiting a length of thread, one clamp being rotatable to untwist the delimited

15 length of thread, a clamp and a spool holder for delimiting a length of another thread, the spool holder and the spool thereon being rotatable together, and means for rotating the rotatable clamp and spool holder

20 to untwist the delimited length of thread and a thread holding clip on the spool holder.

10. A mechanism for splicing threads including in combination a pair of clamps for

25 delimiting a length of thread, one clamp being rotatable to untwist the delimited length of thread, a clamp and a spool holder for delimiting a length of another thread, the spool holder and the spool thereon being

30 rotatable together, and means for rotating the rotatable clamp and spool holder to untwist the delimited length of thread and for rotating the spool holder in the opposite direction to restore the normal twist after splicing the strands of the two threads and a thread holding clip on the spool holder.

11. The method of splicing threads or cords one of which is wound on a spool which comprises clamping a delimited 40 length of each cord and rotating one end of each cord and the spool therewith to untwist the strands of the delimited length and to prevent the creating of back twist in the cords.

45 12. The method of splicing threads or cords one of which is wound on a spool which comprises clamping a delimited length of each cord and rotating one end of each cord and the spool therewith to untwist the strands of the delimited length and to prevent the creating of back twist in the cords and correspondingly rotating the spool after the splice is made to restore the normal twist to the united cord.

55 13. A mechanism for splicing threads including in combination a clamp for delimiting a length of thread from a spool, and cooperating means for holding and rotating the spool of thread at the opposite end of the delimited length to untwist the strands of the delimited length and to prevent back twist in the thread.

60 14. A mechanism for splicing threads including in combination a clamp for delimiting a length of thread from a spool, and

cooperating means for holding and rotating the spool of thread at the opposite end of the delimited length to untwist the strands of the delimited length and to prevent back twist in the thread and a thread 70 clamp on said spool holder.

15. A mechanism for splicing threads including in combination means for untwisting the strands of two threads one of which is wound on a spool, means for correspondingly rotating the spool to prevent the creation of back twist in its thread, and means preventing the removal of the spool during the operation.

75 16. A mechanism for splicing threads including in combination means for untwisting the strands of two threads one of which is wound on a spool and for retwisting the delimited length after splicing, means for correspondingly rotating the spool to prevent the creation of back twist during the untwisting and for restoring the normal twist, and means preventing the removal of the spool during the operation.

80 17. A mechanism for splicing threads including in combination means for untwisting the strands of two threads one of which is wound on a spool, means for correspondingly rotating the spool to prevent the creation of back twist in its thread, and a device 90 for preventing removal of the spool during the rotation thereof.

85 18. A mechanism for splicing threads including in combination means for untwisting the strands of two threads one of which is wound on a spool and for retwisting the delimited length after splicing and means for correspondingly rotating the spool to prevent the creation of back twist during the retwisting and for restoring the normal 100 twist in said length and a device for preventing the thread unwinding from the spool, and means preventing the removal of the spool during the operation.

105 19. A mechanism for splicing threads including in combination a pair of clamps for delimiting a length of thread, one clamp being rotatable to untwist the delimited length of thread, a clamp and a spool holder for delimiting a length of another thread, the spool holder and the spool thereon being rotatable together, means for rotating the rotatable clamp and spool holder to untwist the delimited length of thread, and means preventing the removal of the spool 115 during the operation.

120 20. A mechanism for splicing threads including in combination a pair of clamps for delimiting a length of thread, one clamp being rotatable to untwist the delimited length of thread, a clamp and a spool holder for delimiting a length of another thread, the spool holder and the spool thereon being rotatable together, means for rotating the rotatable clamp and spool 125 holder to untwist the delimited length of thread, and means preventing the removal of the spool during the operation.

holder to untwist the delimited length of thread and for rotating the spool holder in the opposite direction to restore the normal twist after splicing the strands of the 5 two threads, and means preventing the removal of the spool during the operation.

21. A machine for splicing cord comprising an arbor to hold a spool and having a cord-holding means thereon, a second arbor 10 to hold a second cord, means for clamping the said cords opposite said arbors, and

means for rotating said arbors simultaneously.

22. A machine for splicing cord comprising a yielding non-rotatable holder for 15 cords, arbors to which said cords are adapted to be secured, one of said arbors being adapted to support a spool, and means for rotating said arbors.

In testimony whereof, I have signed my 20 name to this specification.

TIMOTHY J. KELLY.
